UNITED STATES PATENT OFFICE

GEORGE LAFAYETTE CHERRY, OF LA GRANGE, ILLINOIS, ASSIGNOR TO WESTERN ELECTRIC COMPANY, INCORPORATED, OF NEW YORK, N. Y., A CORPORATION OF NEW YORK

CLEANING DEVICE

Application filed December 19, 1928. Serial No. 327,027.

This invention relates generally to cleaning and tensioning devices, and more particularly to wire cleaning and tensioning devices for use in wire insulating apparatus. It is 5 desirable in a number of industrial arts to clean wires or other articles before performing some operation thereon, and it is especially important in the manufacture of insulated wire to thoroughly clean the wire before applying an insulating coating thereto. It is 10 particularly desirable in continuous wire insulating apparatus, such as that disclosed in the United States Patent No. 1,689,205, granted October 16, 1928 to L. F. Lam- 15 plough, to not only clean the wire before it is advanced into the apparatus, but also to exert a tension thereon in order that the wire may be advanced at a uniform rate.

The object of the invention is to provide 20 simple, inexpensive and effective devices for cleaning articles and exerting tension thereon.

In accordance with the general features of the invention, one specific embodiment thereof 25 embraces a supply reel from which a wire or cable is advanced through a cleaning and tensioning device comprising a pair of relatively movable arms, each of which carries a plurality of interchangeable, adjustable 30 wiping members, and which may be pressed together by an adjustable pressing means to cause the wipers to forcibly engage a wire positioned therebetween. From the cleaning and tensioning devices the wire is passed 35 through a mechanism provided with an extrusion head which forms a coating of an unvulcanized insulating material upon the wire as it is advanced therethrough, after 40 which the coated wire is passed directly without access to the atmosphere into a vulcanizing chamber in which the insulating material is subjected to sufficient heat and pressure to vulcanize it. The wire emerges from the 45 vulcanizing chamber through a seal which tends to maintain the pressure within the chamber, and is wound upon a storage reel where it may remain until used.

The invention will be clearly understood 50 from the following detail description of a

specific embodiment thereof and the accompanying drawings, in which

Fig. 1 is a side elevation of a wire insulating machine embodying the invention;

Fig. 2 is an enlarged side elevation of a 55 wire cleaning and tensioning device forming a part of the apparatus, and

Fig. 3 is a vertical sectional view thereof taken on line 3—3 of Fig. 2.

Referring now to the drawings, wherein like numerals are employed to designate like parts throughout the several views, the numeral 10 indicates a supply reel from which a wire 11 to be insulated is drawn through the wire straightening device 12 of any desired form by means of capstan 13, around which the wire passes and which is driven through a pulley 14 by means of a belt 15 connected to any suitable source of power (not shown). From the capstan 13 the wire passes 70 through a wire cleaning and tensioning device designated generally by the numeral 18 which is secured by means of an arm 19 to an extrusion mechanism 20 through which the wire is advanced after having been advanced 75 through the cleaning and tensioning device and which is designed to extrude a uniform coating of unvulcanized insulating material on the wire as it emerges therefrom. The extrusion mechanism may be of any well 80 known type and is illustrated only diagrammatically since a complete description of its construction is not essential for a complete understanding of the invention. Preferred 85 types of extruding apparatus are disclosed in the copending application Serial No. 112,599, filed May 29, 1926 by R. C. Kivley, issued as Patent 1,770,985, July 22, 1930, and in my copending application Serial No. 327,028, filed December 19, 1928, issued as Patent 1,770,969, 90 July 22, 1930.

A connecting member 21 such as that described in the copending application Serial No. 223,589 filed October 3, 1927 by R. C. Kivley effects a pressure-tight connection between the extrusion mechanism 20 and a vulcanizing chamber 22, wherein the coated wire is subjected to a vulcanizing medium such as steam under pressure, which completely vulcanizes the insulating material 100

upon the wire, and from which the insulated wire emerges through a seal 24 such as that disclosed in the aforementioned patent granted to L. F. Lamplough, which prevents the escape of more than a predetermined amount of the vulcanizing medium from the interior of the chamber. From the seal 24 the wire, now covered with a vulcanized insulating coating, is drawn around a sheave 25 by means of a capstan 26 and is then delivered to a take-up reel 27 upon which the finished wire is wound and stored.

The cleaning and tensioning device 18, which is designed to clean the wire before it is advanced into the extrusion mechanism 20 and to exert a substantially uniform tension upon the wire so that the wire may be advanced through the apparatus at an approximately uniform rate, comprises a lower channel-shaped arm 30 rigidly secured to the supporting arm 19 and an upper companion channel-shaped arm 32 pivotally secured to the arm 30 by means of a hinge 33, which permits relative movement between the arms 20 30 and 32 in substantially the same plane. The arms 30 and 32 are provided with spacing members 35—35 and 36—36 respectively, which are secured to the arms by means of pins 37 and 38 which extend through the 25 spacing members and the sides of the arms. The arms 30 and 32 are provided with U-shaped notches 40—40 and 41—41 and the spacing members 35—35 and 36—36 are provided with similar aligned notches 42—42 30 and 43—43 into which bolts 45 and 46 may be inserted. Positioned upon each of the bolts 45 and 46 are a plurality of interchangeable, adjustable, circular wiping discs 48—48 and 49—49 made of felt, leather, fabric, or 35 any other suitable yieldable material, so spaced that they may be inserted between the spacing members 35—35 and 36—36.

Pivotally mounted upon the upper arm 32 is an auxiliary arm 51 to which is pivotally 45 secured a latch member 52 which is normally urged downwardly as seen in Fig. 2 by means of a spring 53 pressing against a laterally extending handle portion 54 so that when the arms 30 and 32 are in proximity the 50 lower end of the latch 52 will catch beneath the bottom of the arm 30 and releasably maintain the arms 30 and 32 in proximity. A hollow cylindrical member 56 is secured within an opening 57 in the auxiliary arm 55 51 within which member is positioned a plunger 58 urged downwardly by a spring 59, the tension of which may be adjusted by means of a plug 60 threaded into the upper end of the tubular member 56 in order that 60 the plunger 58 may exert a predetermined pressure upon the upper arm 32 when the arms 30 and 32 are latched in proximity as is clearly shown in Fig. 2.

The operation of the apparatus is as follows: The end of the uncovered wire 11 is

threaded through the wire straightening device 12 around the capstan 14 through the wire cleaning and tensioning device 18, the extrusion mechanism 20, the vulcanizing chamber 22 and the seal 24, around the sheave 25 and capstan 26 and on to the take-up mechanism 27. Power is then applied to the various driven members, a quantity of unvulcanized insulating material such as a suitable rubber compound is inserted into the extrusion mechanism and steam is introduced into the vulcanizing chamber 22, whereupon the wire 11 is covered with an unvulcanized insulating material by the mechanism 20, which material is vulcanized within the chamber 22 to form an insulating coating thereon, the wire cleaning and tensioning device 18 serving to clean the wire and to exert a substantially uniform tension thereon so that the wire is advanced at a uniform rate.

In the insertion of the wire in the wire cleaning and tensioning device 18 the handle portion 54 of the latch 52 and the outer portion of the auxiliary arm 51 are grasped so as to retract the lower end of the latch 52 from beneath the arm 30, and the upper arm 32 and auxiliary arm 51 are rotated in a counter-clockwise direction as seen in Fig. 2 to permit the insertion of the wire between the wiping discs 48—48 and 49—49. When the wire has been positioned between the wiping discs the arm 32 is lowered and secured in proximity to the arm 30 by the latch 52 in which position the wiping discs 48—48 and 49—49 engage the wire 11 from opposite sides thereof and, since they are made of a yieldable material, they partially encircle the wire and press against substantially the entire surface of the wire during its passage therebetween. The force exerted by the discs 48—48 and 49—49 against the wire and the resulting tension applied to the wire by the discs may be varied to any desired value by regulating the tension on the spring 59 by means of the plug 60. When any particular portion of the wiping discs has become worn, additional wiping surfaces may be presented by releasing the bolts 45 and 46 and rotating the discs so as to present other portions of their peripheries and the wiping discs may therefore be utilized for a long period of time before replacements are necessary. When any or all of the wiping discs become too worn for further use, they may be readily replaced with other discs by simply removing the bolts 45 and 46, withdrawing the worn discs and placing new discs thereon.

Although a wire cleaning and tensioning device embodying the invention has been described as incorporated in a wire insulating apparatus, it is of course to be understood that devices embodying the invention are not limited in their use to wire insulating ap-

paratus, but may be utilized wherever it is desirable to clean and/or apply tension upon wires, ribbons, or other articles. Also the specific embodiment of the invention described hereinbefore is merely one of many useful examples of the invention, and the invention embraces any embodiment thereof within the scope of the annexed claims.

What is claimed is:

10 1. In a cleaning device, a pair of relatively movable arms, removable, wiping members positioned on the arms and adjustable with respect thereto, and adjustable means for causing the wiping members to yieldably engage an article positioned therebetween.

15 2. In a cleaning device, a pair of relatively movable arms, a plurality of circular wiping members positioned in cooperative relation on the arms, the wiping members 20 on one arm being staggered with respect to the wiping members on the other arm, and releasable means for retaining the arms in proximity so that the wiping members are maintained in overlapping relationship, 25 whereby they engage and completely surround an article positioned therebetween.

30 3. In a cleaning device, a pair of arms, a plurality of wiping discs positioned on each of the arms, releasable means for retaining the arms in proximity, and adjustable means for pressing the arms together to cause the wiping discs to engage an article positioned therebetween.

35 4. In a wire cleaning device, a series of spaced interchangeable, adjustable, wiping discs, a second series of said discs positioned adjacent the first mentioned series of discs, and adjustable means for pressing said discs toward a common line to cause the discs to 40 forcibly engage from opposite sides a wire positioned therebetween.

45 5. In a wire cleaning device, a pair of arms, means for pivotally joining the arms to permit relative movement thereof, a plurality of spaced wiping members on each of the arms, means for adjusting the wiping members to present different wiping surfaces, and adjustable means for pressing the arms together to cause the wiping members 50 to engage a wire positioned therebetween.

55 6. In a wire cleaning device, a pair of arms, means for pivotally joining the arms, a plurality of spaced interchangeable, wiping discs on each of the arms, means for adjusting the discs to present different wiping surfaces, and combined latching and pressing means for releasably securing the arms in proximity and for causing the wiping discs to forcibly engage a wire positioned there- 60 between.

65 7. In a cleaning device, a pair of relatively movable arms, a plurality of interchangeable, adjustable wiping members positioned upon each of the arms, and combined latching and pressing means for releasably se-

curing the arms in proximity and for causing the wiping members to engage an article positioned therebetween.

8. In a cleaning device, a pair of relatively movable arms, a plurality of interchangeable, adjustable, wiping discs removably secured upon each of the arms, a plurality of spacing members secured to each of the arms for spacing the wiping discs, and combined latching and pressing means for releasably securing the arms in proximity and for causing the wiping members to engage an article positioned therebetween.

70 9. In a wire cleaning device, an arm, a plurality of interchangeable, adjustable wiping discs removably secured upon the arm, a plurality of spacing members secured to the arm for spacing the wiping discs, an arm pivotally secured to the first mentioned arm, a plurality of interchangeable adjustable wiping discs removably secured upon the second mentioned arm, a plurality of spacing members secured to said second mentioned arm, an auxiliary arm pivotally mounted upon the second mentioned arm, a latch carried by the auxiliary arm for releasably securing the other arms in proximity, and adjustable means carried by the auxiliary arm for pressing the other arms together to cause the wiping discs to forcibly engage a wire positioned therebetween.

In witness whereof, I hereunto subscribe my name this 8th day of December, A. D. 1928.
